(57) **CLAIM**

The ornamental design for a dispenser with refill, as shown and described.

DESCRIPTION

FIG. 1 is a perspective view of a dispenser with refill showing our new design;

FIG. 2 is a front elevational view of the new design;

FIG. 3 is a rear elevational view of the new design;

FIG. 4 is a right side elevational view of the new design;

FIG. 5 is a left side elevational view of the new design;

FIG. 6 is a top plan view of the new design; and,

FIG. 7 is a bottom plan view of the new design.

The broken-line disclosure is understood to represent portions of the article in which the claimed design is embodied, but which form no part of the claimed design.
